(57) **CLAIM**

The ornamental design for a blade for a folding knife, as shown and described.

DESCRIPTION

FIG. 1 is a perspective view of the blade for a folding knife showing my design.

FIG. 2 is a top plan view thereof;

FIG. 3 is a front elevation view thereof;

FIG. 4 is a side elevation view thereof;

FIG. 5 is a back elevation view thereof;

FIG. 6 is a bottom plan view thereof;

FIG. 7 is an opposite side elevation view thereof; and,

FIG. 8 is an exploded perspective view thereof with a handle of a folding knife in broken lines.

The broken line showing of the knife assembly in FIG. 8 is provided for purposes of environment and forms no part of the claimed design.
